US00D449532B2

(12) United States Design Patent
Modjeski

(10) Patent No.: US D449,532 S
(45) Date of Patent:  Oct. 23, 2001

(54) CONTAINER

(75) Inventor: Lara Modjeski, New York, NY (US)

(73) Assignee: Polo Ralph Lauren Corporation, New York, NY (US)

() Term: 14 Years

(21) Appl. No.: 29/118,350

(22) Filed: Feb. 3, 2000

(51) LOC (7) Cl. 09-01

(52) U.S. Cl. D9/500; D9/545; D9/574

(58) Field of Search D9/300, 302, 337-339, D9/341, 347, 414, 418, 430, 448-450, 500, 503-504, 516, 520-523, 529, 530, 535, 526, 545, 548, 549, 574-575; 206/432; 215/382-384, 6; 220/780-783; 222/206, 212-213, 215, 321.7-321.9

UNITED STATES PATENT AND TRADEMARK OFFICE
CERTIFICATE OF CORRECTION

PATENT NO. : Des 449,532 S
DATED : October 23, 2002
INVENTOR(S) : Lara Modjeski

Page 1 of 3

It is certified that error appears in the above-identified patent and that said Letters Patent is hereby corrected as shown below:

Title page,

Showing the illustrative figure, should be deleted and substitute therefor the attached title page.

Drawings,

The Sheet of drawings, consisting of FIGS. 1 – 4, should be deleted and substitute therefor the sheet of drawings consisting of FIGS. 1 – 4, as shown on attached page.

Signed and Sealed this

Ninth Day of July, 2002

Attest:

Attesting Officer

JAMES E. ROGAN
Director of the United States Patent and Trademark Office
